APPARATUS FOR PRINTING OF AMOUNTS BEING ROUNDED OFF BEHIND THE DECIMAL POINT IN CALCULATING MACHINES

Helmut Geiling, Ulm (Danube), Germany, assignor to
Walther Büromaschinen Gesellschaft m.b.H., Essen,
Germany, a firm

Filed Apr. 27, 1959, Ser. No. 809,141

Claims priority, application Germany May 6, 1958
11 Claims. (Cl. 235—61)

The invention relates to an apparatus of calculating machines having a shiftable main totalizer, a differential mechanism, a printing device, and a multiplying device, arranged for printing of products or other amounts from the main totalizer which will be struck off and rounded off behind the decimal point in a denominational correct manner.

With such machines the decimal point position of the product or the like of the main totalizer has to be brought into agreement with the decimal point position of the differential mechanism, the printing device and the auxiliary totalizers by corresponding shifting the totalizer slide in order that all amounts to be printed are correctly superpositioned, or the amounts of the main totalizer can be transmitted to the auxiliary totalizer in a denominational correct manner.

The number of denominations of the product on the right of the decimal point, corresponding to the sum of the number of the denominations of the multiplicand and the multiplier, has the effect that the totalizer slide is to be shifted to the right by a certain number of denominations, mostly by the number of denominations of the multiplicator on the right of the decimal point. This shifting is to be performed after the termination of the multiplication in which the totalizer assumes its normal position and in which the outermost right denominations of the differential mechanism and the totalizer register with one another, when it is the decimal point position of the multiplicand introduced into the differential mechanism which has to determine the decimal point position of the product.

In this instance a corresponding number of the last denominations on the right of the main totalizer come out of the region of the differential mechanism so that these denominations will not be printed and consequently being struck off.

It is known in the art, to increase by one actuation unit the last denomination on the right to be printed, when the highest denomination to be rounded off represents a digital value of five and more. This rounding off will be brought about by adding five units to the highest denomination to be struck off.

With the above mentioned kind of calculating machines to which the invention relates, the functions of the machine necessary for the rounding off and the movement of the totalizer slide into the correct comma position will be set and performed, one after the other, by hand. This takes up much time and easily leads to mistakes.

In order to avoid these drawbacks according to the invention, there is annexed to the multiplication and to the setting of the denominations on the right of the decimal point to be struck off a striking off-cycle of operation of the machine which is initiated by the rounding off means, during which, in the first place, in the normal position of the totalizer slide five units will be added to the highest denomination to be struck off, subsequently whereof the totalizer slide will be moved from its normal position to the right by a number of denominations corresponding to the number of the denominations to be struck off, and at the end of this movement all driving and control

2

parts will be returned into the normal position, and the drive mechanism will be arrested.

In order to set the denominations to be rounded off a transversely shiftable setplate is provided for which is provided with a locking edge for locking the differential members in their normal position, a recess in said locking edge for releasing one of the differential members by five units, and a stepped lug for adjusting a step controlling means for the denominational shifting of the totalizer slide.

At the end of the multiplication, the rounding off means being will be operated, the totalizer slide assumes its normal position, the differential members with exception of the one of the highest denomination to be struck off will be locked in their normal position, the striking off-cycle of operation of the machine will be automatically initiated by the movement of the restoring bar into its stroke end position under transmitting the five rounding off units into the multiplying mechanism, and the starting 20 of the multiplying device, the disengaging of the actuation of the revolution counter, and of the step controlling organ for the movement of the totalizer slide into the correct denominational transmitting position will be prepared.

At the end of the multiplication a leverplate, operatively connected with the restoring bar bar by means of the rounding off means will be displaced, whereat the leverplate locks itself in its rocking position, brings the shiftable setplate in the locking position for the differential members, engages the coupling for the restoring bar for the actuation of the differential members, releases the step controlling means locked in its position of rest for the movement towards the adjusted step, and puts a lug into the path of the restoring bar by which lug, on being struck by the restoring bar in its stroke end position at the end of the revolution of the multiplying device the totalizer shifting coupling will be engaged and the actuation of the revolution counter will be disengaged.

The step controlling organ consists of a spring urged 40 rod, which senses the steps of the setplate by a finger and provides for two ratchet gearings, the one of which co-operating with a retrograde locking pawl whilst the other one being in engagement with a actuating pawl which restores the step controlling organ into its normal position during the rounding off operation.

At the end of the single revolution of the multiplying device on the striking off and rounding off operation the coupling of the multiplying device will be disengaged whilst the coupling for the shifting of the totalizer slide will be engaged. This engagement will be secured by a locking device until, on the step movement of the step controlling organ, a lug connected therewith releases the locking device.

Further features of the invention result from the following description of an example of embodiment of the invention.

In the accompanying drawing:
FIG. 1 is a scheme of the arrangement of the main 60 mechanisms of the calculating machine.

FIG. 2 is a side elevational view of the setting, controlling and drive parts utilized for the rounding off operation.

FIG. 3 is a top view of the parts of FIG. 2 together 65 with a part of the totalizer slide and the set pin carriage.

FIG. 4 is a side elevational view of the drive mechanism for the restoring bar.

FIG. 5 is a side elevational view of the three utilized 70 drive couplings together with the controlling levers for the slide shifting coupling.

FIG. 6 is a side elevational view of a part of the

controlling means and the disengaging device of the revolution counter.

FIG. 7 is a detail.

FIG. 8 is a side elevation of an actuating rack and parts coacting therewith.

Rounding Off of Decimal Fractions

The invention is determined for the application to a calculating machine of the kind according to the scheme illustrated in FIGURE 1. The differential mechanism provides differential members in the form of actuating racks 1 located side by side, one for each denomination, on to which the amount set by the setting mechanism 2 will be transmitted and through multiplying mechanism 3 arrives at a main totalizer 4. The main totalizer is mounted in a slide 5 or carriage which is shiftable from denomination to denomination.

The setting mechanism may be, as is illustrated, of the ten key type with which the digits of the depressed keys of the amount to be introduced (multiplicand or items), at the first place, arrive at a set pin carriage moved step by step, the set pins of which displaced by the keys form lugs for the adjustment of spring urged differential members or actuating racks 1, when they have been released from a joint restoring bar.

On adding, with which the main totalizer is retained in the illustrated normal shifting position in which its outermost right counting wheel 6 being placed in the plane of the outermost right toothed rack 1, the introduced amount will be transmitted, by a single revolution of the multiplying mechanism 3, from the actuating racks 1 to the main totalizer 4, or to stationary auxiliary totalizers 7, or storing devices.

Simultaneously, the introduced amount may be printed by means of printing mechanism the type carriers 8 of which being adjusted by the actuating racks to a paper-sheet or paperstrip 9 of a laterally movable or nonmovable paper carrier.

When, on such adding, the added items having corresponding decimal point positions are introduced and striking off of denominations on the right of decimal point is not to be performed, as the main totalizer is retained in its normal position, on transmitting of a value from the main totalizer onto an auxiliary totalizer, or the printing mechanism 8, a movement of the main totalizer out of its normal position is not necessary. For effecting multiplications the multiplying mechanism 3 more fully explained further on will be set through the actuating racks 1 according to the multiplicand and caused to a number of revolutions corresponding to the different digits of the multiplier, whereat the calculated partial products will be transmitted to the main totalizer, which will be shifted to the right from denomination to denomination.

The control of the revolutions of the multiplying mechanism and of the stepwise shifting of the main totalizer to the right and likewise the returning of the main totalizer at the end of the multiplication into its normal position will be performed by a multiplier mechanism 11, further explained below, in which the multiplier, set, before the entering of the multiplicand, by means of the setting mechanism 2 or particular multiplier keys will be stored. On the revolution of the multiplying mechanism the multiplier digits will be denominationaly transmitted to the revolution counter 12, which is unshiftably lodged in the machine, but which may also be placed on the slide for the main totalizer.

As far as the multiplier represents a whole number which case may be indicated by the position 13' of the decimal point slide 13 of the revolution counter the value of the main totalizer will be transmitted, when the totalizer slide again assumes its normal position, to the auxiliary totalizer 7 and to the printing mechanism 8 in a denominationaly correct manner, no matter whether the multiplicand is a decimal fraction or a whole number. When, however, the multiplier represents a decimal frac-

tion, the number of denominations on the right of the decimal point are summed up from that of the multiplicand and that of the multiplier. In the case in which the multiplicand of the decimal fraction or a whole number nations the product has five denominations on the right of the decimal point, as may be indicated by the positions 14' of the decimal point slide 14 for the main totalizer.

When the product is to be transmitted onto an auxiliary totalizer 7 or the printing mechanism 8 in a fixed decimal point position (decimal point slide 14), for instance, in the decimal point position of the multiplicand, therefore, the slide 5 of the main totalizer must be shifted by a corresponding number of orders to the right, here three denominations, whereat the three outermost denominations on the right of the main totalizer come out of the region of the actuating racks 1 being separated out of the further calculating operations and consequently have to be considered as being struck off.

It is desirable to increase the outermost right, not struck off denomination of the fraction by one unit when the highest denomination being struck off represents the digital value "5" or more.

This rounding off is to be brought about previously to the shifting of the totalizer to the right, if it is intended to perform the rounding off by means of one of the actuating racks.

Naturally, the said shifting of the main totalizer is to be performed by another number of denominations in the case that the value of the product is to be increased or decreased by a number of denominations, for instance in percent calculations. For the understanding of the machine function necessary for the striking off and rounding off the mechanisms participating therein and being utilized for the normal multiplication without rounding off will be, in the following, briefly explained.

General Structure of the Utilized Calculating Machine

The actuating racks 1 (FIG. 3) are urged by tension springs 15 (FIG. 2) and cooperate with a joint restoring bar 16 by which they usually will be held against the actions of their springs 15 in their normal position represented in FIG. 2.

The restoring bar 16 is attached at its ends to drawing rods 17 (FIG. 4) which are guided at their other ends by links 18, seizing by means of slots 19 over crank pins 20 of crank arms 22 of a drive shaft 21.

On the first half revolution of the shaft 21 the restoring bar 16 (FIG. 2) will be moved out of its normal position into its stroke end position represented by dash and dot lines 16', whereat the actuating racks 1 with lugs 23 strike and being arrested by adjusted set pins 24 of the set pin carriage 25. The set pin carriage is mounted transversely shiftably on two cross rods 26, 27 (FIG. 2).

For the execution of a complete multiplication followed by the particular cycle of operation for rounding off, which is alone to be taken into consideration for the invention, in the first place, the multiplier will be entered into the set pin carriage by means of the digit keys of the setting mechanism by depressing the set pins 25 and then the multiplier key 256 (FIG. 1) will be depressed.

By so doing, a cycle of operation is released on which the multiplier will be transmitted to the multiplier mechanism 11 through the actuating rods 1 (FIG. 8). The multiplier mechanism consists of ordinarily arranged, horizontally guided racks 257 having ratchet teeth, usually urged to the right by springs 258 into the illustrated normal position, in which they contact by means of an ear 259 fingers 260 of the actuating rods.

On shifting of the actuating rods 1 to the right according to the multiplier, the ratchet racks 257 will be taken along by the fingers 260 and held fast by spring urged retrograde pawls 261 in their set positions.

After that, the multiplicand will be set by means of the digit keys of the setting mechanism 2 and transmitted

thereby to the set pins 24 of the set pin carriage 25. Then the multiplication key 28 (FIG. 2) will be depressed. By so doing, a series of cycles of operations will be initiated on which the product of the multiplication of the multiplier and the multiplicand is formed in the multiplying mechanism 3 (FIG. 8).

The multiplying mechanism has the form of a pawl actuating mechanism, for instance, according to the subject matter of the U.S. Patent specification No. 2,824,691. On a shaft 262 (FIG. 8), which is permanently rotated after the multiplying mechanism coupling 32 (FIG. 5) has been engaged, in each order a holding member 263 for a pawl 264 is provided for.

The pawl 264 cooperates with a ratchet gear 265 of an actuating ring 266 which coacts by means of an external toothed 267 with the main totalizer 4.

The engagement of the pawl 264 into the ratchet gear 265 is controlled by a cam notch 268 located on a setting disc 269, engaging the actuating rod 1 of the respective order and adjusted according to the respective digit of the multiplicand by the movement of the actuating rod 1 to the right on the releasing of the restoring bar 16.

During the first cycle of operation of the series of cycles of operations initiated by the multiplication key 28 the restoring bar 16 will remain, after the first half of revolution of the driving shaft 21 (FIG. 4), in its position 16' (FIG. 2) until the end of the multiplying operation, since a restoring bar coupling 29 (FIG. 5) connecting the shaft 21 with the drive mechanism of the machine will be disengaged. At the same time a multiplying mechanism coupling 32, mounted on a shaft, 31 (FIG. 5) will be engaged, this coupling being arranged between the drive mechanism of the machine and the multiplying mechanism 3 (FIG. 1). Thereby, the holding member 263 of the multiplying mechanism will be turned performing in each order a number of revolutions corresponding to the respective digit of the multiplier under the control of the multiplier mechanism 11, whereat the multiplicand will be added corresponding times onto the main totalizer in the concerned position of the 40 totalizer slide. Subsequently, the totalizer slide 5 will be moved by one denomination to the right. This will be brought about by the engagement of a slide shifting coupling 33 (FIG. 5), mounted on a shaft 34. Further revolutions of the multiplying mechanism will be annexed according to the digital value of the pre-set multiplier under corresponding stepwise shifting of the totalizer slide 5 (FIG. 1). The controlling of the number of revolutions of the multiplying mechanism 3 according to the multiplier set in the multiplier mechanism 11 is caused by the stepwise returning of the ratchet rack 257 (FIG. 8) into its normal position in the following manner:

Below the ratchet rack 257 (FIG. 8) a square shaft 270 is rockably mounted on which an axially shiftable slide piece 271 is arranged mounting by means of a pin 272 an actuating pawl 273 cooperating with the ratchet racks 257 and moving the respective ratchet rack 257 by one pitch to the left on rocking counterclockwise of the shaft 270.

The rocking of the shaft 270 is caused by an arm 274 secured to the shaft 270 by means of a rod 276 linked to said arm by means of a pin 275. The rod 276 is provided with an open slot 277 cooperating with an eccentric pin 278 of a shaft 279.

The shaft 279 (FIG. 6) is operatively connected by means of toothed wheels with the driven part of the multiplying coupling 32 (see also FIG. 5).

On engaging this coupling, therefore, also the shaft 270 (FIG. 8) will be rocked, the eccentric pin 278 being in mesh with the slot 277, on each revolution of the multiplying mechanism 3 and returns the respective ratchet rack 257 by one step. When the latter arrives at its normal position, the multiplying mechanism coupling will be disengaged and the slide piece 271 will be moved below the adjacent ratchet rack 257 and the totalizer slide

5 will be moved by one order to the left (FIG. 1). After performance of the revolutions of the multiplying mechanism 3 according to the last denomination of the pre-set multiplier, the totalizer 4 contains the product and will be automatically returned to the left into the normal position illustrated in FIG. 1.

Then, on the termination of the multiplying operation the restoring bar coupling 29 (FIG. 5) will be again engaged in order to cause the second half of the revolution of the crank arm 22 (FIG. 4) by means of the shaft 21 whereby the restoring bar 16 (FIG. 2) will be returned again into its normal position situated on the left, and in a given case the printing of the product by the printing mechanism 8 (FIG. 1) and the transmitting 10 15 onto the auxiliary totalizer 7 takes place, the set pin carriage will be returned to its normal position, and the setting mechanism of the machine will be released.

In order to put into action the multiplying mechanism, after the first half of the revolution of the shaft 21 (FIG. 4) has been terminated, during which the adjustment of the setting mechanism has been transmitted onto the multiplying mechanism 3 by means of the actuating racks 1 (FIG. 1), on depressing of the multiplication key 28 (FIG. 2) a lever 38 linked to a pin 36 and urged by a spring 37 had been rocked downward into the path of the restoring bar 16 by means of a pin 35 fixed to the multiplication key 28 (FIG. 2). The pin 36 is secured to an arm 40 mounted on a stationary pin 39. To the arm 40 a rod 41, which leads to the multiplying mechanism coupling 32 (FIG. 5) is linked. When the restoring bar 16, at the end of its movement to the position 16', strikes the left end of the lever 38 (FIG. 2), this lever will be moved to the right engaging the multiplying coupling through the rod 41 so that the multiplying mechanism subsequently accomplishes its revolutions in dependence on the multiplier mechanism 11.

The mentioned three drive couplings for the restoring bar, the multiplying mechanism and the slide shifting 29, 32, 33 (FIG. 5) are provided, in a known manner, with coupling pawls 42, 43, 44 loosely mounted on the shaft 45, which rotate together with the driven parts of their couplings and cooperate with stop levers 46, 47, 250 (FIG. 6), 48 (FIG. 5) in such a manner that the stop levers, as illustrated, usually hold the coupling pawl in their disengaged positions thereby disengaging the couplings, and upon moving the stop levers away from the coupling pawls the coupling will be engaged, in order to rotate the corresponding drive shafts 21, 31, 34.

The couplings rendered effective will be disengaged 50 when the stop levers are returned in the path of the coupling pawls. The stop levers are under the action of springs by which they are urged to rock into their releasing position. They will be usually held in their stop-position by locking levers rotably mounted on a rod 49 (FIG. 6). The stop lever 46 for the normal position of the restoring bar coupling bears, with its arm 59, on a lug 51 of the associated locking lever 52; the stop lever 250 for the 180° position of the restoring bar coupling bears with its arm on the lug of the associated locking lever 252 (FIG. 3); the stop lever 47 for the multiplying mechanism coupling with its arm 53 bears from below on a lug 54 of the associated locking lever 55, and the stop lever 48 (FIG. 5) for the slide shifting coupling bears with an arm 56 on a lug 57 of the associated locking lever 58. The released stop levers will be restored from their released position into their stop position by means of rollers mounted on them and tensioning cams of the driven coupling parts. As far as it will be necessary for the understanding, these 60 65 70 75 devices will be hereinafter more fully explained.

Preparation of the Rounding Off and Striking Off Operation

If subsequently to the effectuating of a product by the multiplying mechanism the shifting of the totalizer slide

into the denominational correct decimal point position and the striking off of denominations to the right of the decimal point and rounding off is to be performed, previous to the beginning of the calculation a rounding off lever 59 rockably mounted on the pin 39 (FIG. 2) is to be adjusted into the dotted position 59'. Further, a handle 60 (FIG. 3) is, in a given case, to be set, corresponding to the number of orders to the right of the decimal point to be struck off, and to put into action the machine by depressing the multiplication key 28 (FIG. 2).

By setting the rounding off lever 59 in the position 59' a connecting rod 63 linked to a pin 64 at its lower end will be moved downwards at the right end by means of a link 61 and a connecting pin 62 whereby a projection 65 of the rod arrives at the position 65' moving behind the already mentioned pin 36. The connecting rod 63 is linked by means of the pin 64 to a latch 66, which is connected with a lever plate 68 by a pin 67 and cooperates by means of a lug 69 with the restoring bar 16.

The lever plate 68 is loosely mounted on a shaft 70 and is influenced by a spring 71.

When the restoring bar 16, on its movement to the right, attains the position 16' and displaces the lever 38 to the right the pin 36 carries the projection 65 preadjusted in the position 65' along to the position 65'', so that the connecting rod 63 counter clockwise lifts the latch 66 about its pin 67 bringing the lug 69 into the position 69' in the path of the restoring bar 16. In this specified position the latch 66 is held by a locking lever 72 loosely mounted on a pin 73 of the lever plate 68 and urged by a spring 74, the free right end of the locking lever 72 being placed before the raised pin 64 in the position 64'. On the return movement of the restoring bar 16 into the normal position at the end of the multiplying operation the lug 69 will be struck by the restoring bar and the lever plate 68 will be rocked to the left, whereat the pin 67 arrives at the position 67'. By the rocking of the lever plate 68 the latch 66 will be pressed in its normal position by the restoring bar, so that, after the lever plate 68 has fallen backwards into its illustrated normal position the lug 69 of the latch 66 again is placed out of the path of the restoring bar.

Controlling Operations by the Rocking to the Left of the Lever Plate at the End of the Multiplying Operation

By this rocking to the left of the lever plate 68 at the end of the multiplying operation, now, the control operations required for the rounding off and the rectification of the denominational position are brought about. The mentioned handle 60 (FIG. 3) for the setting of the denominations to be rounded off is connected with a setplate 75 which is provided with a locking edge 76 cooperating with the actuating racks 1. Said locking edge is provided with a recess 77, the depth of which corresponds to five actuation units. At its right end the plate 75 is provided with four steps 78 of equal height.

The setplate 75 is rockably and shiftably mounted on a stationary mounted cross rod 80 by means of supporting arms 79.

On the same cross rod 80 arms 81 are secured which at their left ends carry a rod 82 (FIG. 2), which, by means of a link 83, a two armed lever 85 loosely mounted on a stationary pin 84 and a link 86 is connected with said lever plate 68, by a pin 87. A sheet metal strip 88 is secured to and bent about the rod 82, which guides in its free ends a locking bolt 89, which is pressed against the setplate 75 by the action of a spring 90 and can enter holes 91 (FIG. 3) in order to yieldingly hold the plate in one of its four shifting positions. In each of the shifting positions the recess 77 is placed above one of the four right hand actuating racks 1, one of the four steps 78 being, at the same time, adjusted in the path of a finger 92.

The finger 92 is a part of a step controlling organ in

10 the form of an actuating rod 93 (FIG. 2) which is longitudinally shiftable by means of a slot 94 on the cross rod 80 and guided, at its right end, by a link 95, which is connected with the actuating rod 93 by means of a pin 96 and with its other end attached to a pin 97.

15 The actuating rod 93 is provided at the middle and at the right end each with a ratched gearing 98 or 99, respectively. It is urged, by a spring 100 at its right end to the right and is usually locked against a movement to the right by the engagement of a bent over ear 101 into the ratched gearing 98. The object of the actuating rod 93, together with the set plate 75 is to control the shifting of the totalizer slide into the decimal point right position after the rounding off has been accomplished.

20 The actuating racks 1 are provided on their lower side at the left end with locking noses 102 (FIG. 2), behind which the locking edge 76 is moved when, after the termination of the multiplication, the lever plate 68 will be rocked to the left by the restoring bar 16.

25 When during the striking off cycle of operation, subsequently to the multiplying operation, the restoring rod 16 will be moved again to the right, the actuating racks 1 with the exception of those over which the recess 77 (FIG. 3) is placed, cannot follow the pull of their springs

30 15 (FIG. 2) as they are retained by the locking edge 76 by means of their locking noses 102. The actuating rack 1 situated vertically above the recess 77 is enabled to be displaced under the action of its spring 15 (FIG. 2) by five actuation units and to actuate correspondingly

35 the multiplying mechanism, so that on the following single striking off revolution of the multiplying mechanism five units being added to the corresponding denomination of the main totalizer.

40 In the right hand side position of the setplate 75 in FIG. 3, in which the finger 92 is placed opposite the outermost left step 78 and the handle 60 is in the position "1," one denomination is to be rounded off. When two denominations have to be rounded off, the handle 60 is to be adjusted into the position "2" and so on. A setting position "0" for the handle 60 and the plate 75 need not be provided for as, if no denomination shall be rounded off, the rounding off setting lever 59 (FIG. 2) will not be set and therefore a rounding off cycle of operation subsequently to the multiplying operation does not take place.

45 It will be apparent, that in this manner, the denomination to which on rounding off five units will be transmitted is struck off too and therefore always the five units will be added to the highest denomination to be struck off.

50 By the rocking to the left of the lever plate 68 (FIG. 2) at the end of the multiplying operation the following changes being made:

55 (1) The lever plate 68 will be locked in its left hand position;

(2) The actuating rod 93 will be moved into a preparation position for the control of the slide shifting;

(3) The actuating racks 1 will be locked for the performing of the rounding off;

60 (4) The restoring bar coupling 29 will be engaged;

(5) The engagement of the multiplying mechanism for the rounding off cycle of operation in the position 16' of the restoring bar will be prepared through the restoring bar drive;

65 (6) The engaging of the slide shifting will be prepared by means of the multiplying mechanism coupling;

(7) The disengaging of the revolution counting mechanism will be prepared for the rounding off cycle operation.

70 To (1) A pin 103 is secured to the lever plate 68 (FIG. 2) which on the rocking of the lever plate to the left, moves into the position 103' thereby clockwise rocking two levers 104, 105 about their joint stationary pivot 103, said levers 104, 105 having angle shaped arms and being under the action of springs 106, 107. The

lever 105 is moved with a notch 109 over the pin 103 assuming the position 103' locking the lever plate 68 in its left position.

To (2) The lever 104 will be moved by lifting the pin 103, thus that the above mentioned bent over ear 101 mounted on the lever 104 attains the position 101' freeing the actuating rod 93 for the movement to the right, so that the rod 93 will be moved with its finger 92 onto the step 78 (FIG. 3) of the set plate 75 being in its path, moving to the right by one to four pitches of the ratchet gearings 98, 99 (FIG. 2) according to the lateral adjustment of the set plate 75.

To (3) As described above, by the rocking to the left of the leverplate 68 (FIG. 2) the setplate 75 will be rocked into its locking position 75', in which it locks all actuating racks, with exception of that which is placed above the recess 77 (FIG. 3) of the setplate.

To (4) In order to engage the restoring bar coupling 29 (FIG. 5) for the purpose of moving the restoring bar 16 into the position 16' for transmitting the five rounding off units to the multiplying mechanism and of rocking the leverplate 68 (FIG. 2) to the left the latter is linked to a connecting rod 111 by means of a pivot 110 (FIG. 2), which at its other end is shiftably mounted on a stationary pin 113 by means of a slot 112 and cooperates by means of a finger 114 with the locking lever 52 for the restoring bar coupling 29, said locking finger being mounted on the locking lever axle 49. The upper arm of the locking lever 52 locks, as already mentioned, with its lug 51 usually the stop lever 46 for the restoring bar coupling 29, which stop lever 46 is mounted on the axle 45 (FIG. 6).

When the lever plate 68 (FIG. 2) is rocked to the left the stop lever 46 will be released from the locking lever 52 through the connecting rod 111, so that immediately thereupon the restoring bar coupling will be engaged, the restoring bar 16 will be moved to the right into the position 16', and will be stopped in this position by the stop lever 250 which strikes against the coupling pawl 42. Thereby the actuating rack which is placed above the recess 7 of the setplate 75 transmits five units to the multiplying mechanism, whilst the other actuating racks will be retained by the locking mechanism 76, 102.

To (5) For the rounding off operation the multiplying mechanism is not put into action such as on multiplication by the multiplier 11 but by an additional mechanism. In order to put into action the multiplying mechanism when the restoring bar in the course of the rounding off cycle of operations has attained its position 16', the lever plate 68 has rigidly connected thereto over a connecting rod 115 (FIG. 2) and a slotplate 116 (FIG. 7), likewise mounted on the shaft 70, in the slot 117 of which engages a pin 118 of a lever 120. The lever 120 is loosely mounted on a stationary pivot 119 and its right end, on rocking of the lever plate 68 (FIG. 2) to the left by means of a pin 121, lifts a push rod 122 with a lug 123 into the region of a bent over lug 124 (FIG. 6) of the already mentioned locking lever 95 for the stop lever 47 of the multiplying mechanism.

The push rod 122 (FIG. 6) is linked by means of a pin 255 to a two armed lever 126, mounted on a stationary pivot 125. Said two armed lever 126 will be rocked, in a manner explained below, when the restoring bar arrives at the position 16' in order to release the multiplying coupling.

To (6) When, during the striking off cycle of operation, the restoring bar attains the position 16' it strikes against a nose 134 (FIG. 2) of a pawl 130 urged by a spring 133 and linked by means of a pivot 131 to a lever 132 loosely mounted on the pivot 103. Into a triangular opening 129 of the pawl 130 engages a pin 128 of the lever 105. When struck the pawl 130 causes clockwise rocking of the lever 132 about the bearing pin 103. Thereby, a link 136 connected with the lever 132 by means of a pin, will be shifted to the right, said link 136

being connected with a two armed lever 137 by means of a pin 138. The lever 137 is mounted on the locking lever axle 49 and carries at its other end the already mentioned pin 97 which moves, on shifting the lever 132 to the right, into the position 97' causing thereby transpositions serving for the totalizer slide shifting as will be described below.

To (7) The movement of the nose 134 (FIG. 2) of the pawl 130 into the path of the restoring bar 16 simultaneously represents a preparation for the disconnection of the actuation of the revolution counter 12 during the rounding off operation. For this purpose, the mentioned pivot 131 cooperates with a link 139 (FIG. 6) in a manner described below.

Operations on Arriving of the Restoring Bar at the Stroke End Position During the Rounding Off Cycle of Operation

When the restoring bar 16 after the engagement of the restoring bar coupling 29 (FIG. 6) caused by the rocking of the lever plate 68 (FIG. 2) to the left arrives at the position 16' (FIG. 2), a pin 140 (FIG. 6) acts on the upper arm 141 of the lever 126, whereby the push rod 122 lifted by the rocking of the leverplate 68 will be moved to the left, so that its lug 123, in the preparation position 123', strikes the bent over lug 124 and rocks clockwise the locking lever 55, whereby the stop lever 47 will be released for a rocking to the right and the multiplying mechanism coupling 32 will be put into action, however, but for one revolution. This coupling, namely, is provided with a tensioning cam 142, which acts, at the end of a revolution on a roller 143 rotatably mounted on the stop lever 47 returning the stop lever 47 into its normal position so that the coupling pawl 43 runs up on it disengaging the multiplying mechanism coupling. At the same time the left end of the stop lever 47 again moves below the lug 54 of its locking lever 55, in order to lock the stop lever 47 in its stop position.

When the restoring bar 16 arrives at their outermost position to the right 16' it further displaces, as already explained above, the pivot 97 (FIG. 2) into the position 97'. By lifting the pivot 97 the actuating rod 93 will be lifted at its right end over the link 95 whereby the ratchet gearing likewise will be lifted arriving at the position 99'.

On the pivot 97 a three armed lever 145, urged by a spring 144, is rotatably mounted, the upper arm of which, on the movement of the pivot 97 into the position 97', puts on a rod 146 of a two armed lever 148 rotatably mounted on a stationary pivot 147. This lever 148 cooperates by means of a roller located at its upper end likewise with the tensioning cam of the multiplying mechanism coupling 32.

The stop lever 48 (FIG. 5) for the slide shifting coupling 33 rotatably mounted on the stop lever shaft 45 is locked, as already described, in the represented stop position by a lug 57 of the locking lever 58 of the shaft 49. The locking lever 58 is provided with an arm 150 carrying a lateral pin 151. Below this pin 151 (FIG. 2) an arm 152 of the three armed lever 145 extends. When now the bar 146, with which the upper arm of the lever 145 has come in contact, is moved to the right by the tension cam 142 of the multiplying mechanism coupling, the lever 145 will be rocked clockwise about the pivot 97 being in the position 97', so that its left arm 152 lifts the pin 151 of the locking lever 58 (FIG. 5) rocking the latter clockwise, so that the stop lever 48 will be freed from the lug 57 and accomplishes a clockwise rocking by which the slide shifting coupling 33 will be disengaged at the end of the one revolution of the multiplying mechanism.

Simultaneously with the shifting of the pawl 130 to the right caused by the restoring bar 16 on arriving at the position 16' (FIG. 2) the lever 105 will be clockwise rocked by striking upon the left wall of the recess 129 against the pin 128. Thereby the notch 109 of the lever 105 frees the pin 103 of the lever plate 68, so that the latter can move again into its right normal position under

the action of its spring 71. At the same time, also the lever 104 will be released from the pin 103 so that its bent over ear 101 again engages the ratchet gearing 98 locking the actuating rod 93 against a return movement to the right, when it will be stepwise moved to the left by the mechanism described further below.

Shifting of the Totalizer Slide to the Right

The three armed lever 145 (FIG. 2) is provided with an upturned ear 153 cooperating with a notch 154 of a lever 155 loosely mounted on the shaft 49 and urged by the spring 144. The lower arm 156 of the lever 155 puts, in the normal position of the link 95 illustrated in FIG. 2, on a pin 157 of the link 95 so that the notch 154 of the lever 155 usually is prevented from moving below the upturned ear 153 when the latter has been lifted by rocking of the lever 145. By moving, now, the stop actuating rod 93 onto one of the steps 78 (FIG. 3) and by moving the pivot 97 (FIG. 2) into the position 97', the pin 157 will be remoted from the arm 156 so that the notch 154, now, is enabled to move below the ear 153 when it is lifted at the end of the multiplication revolution by the tension cam 142.

The lever 145 and therewith over the pin 151 also the locking lever 58 (FIG. 5) remain locked in their rocking position to the right by the locking 153, 154, so that the slide shifting coupling can rotate until this locking will be terminated.

The driven part of the slide shifting coupling 33 (FIG. 6) engages into a toothed wheel 158 of a shaft 159, on which a helically formed rib 160 (FIG. 3) is secured engaging a toothed rack 161 of the totalizer slide 5, shifting the totalizer slide on each revolution of the shaft 159 by one denominational space.

The shaft 34 (FIG. 3) of the slide shifting coupling 33 is provided with a disc 162 FIG. 2, carrying a pin 163 cooperating with the upper arm 164 of a two armed lever 165 rotatably mounted on the pivot 147. To the lower arm 166 of the lever 165 is linked an actuating pawl 168 by means of a pivot 167 which together with the lever 165, is urged by a spring 169. The rocking of the pawl 168 on the arm 166 is limited by a pin 170 entering a bore of the arm 166. The actuating pawl 168 cooperates by means of an upturned lug 171 with the above mentioned ratchet gearing 99 of the step actuating rod 93, the gearing 99 being in the position designated with 99'. On each revolution of the shaft 34, therefore, not only the totalizer slide will be moved to the right by one step, but at the same time also the actuating rod 93 will be displaced by one step to the left by the engagement of the upturned lug 171 into the ratched gearing 99, whereby the bent over ear 101 of the released lever 104 cooperates with the ratchet gearing 98 of the actuating rod acting as a retrograde pawl.

On the continued step movement of the rod 93 to the left the pin 157 approaches again stepwise the arm 156 and turns clockwise the lever 155 during the last step, by which the actuating rod 93 on the movement onto the adjusted step 78 (FIG. 3) had been displaced so that the locking 153, 154 (FIG. 2) will be again terminated, the pin 151 and the locking lever 58 (FIG. 5) being released for a clockwise movement. Now, the locking lever 58 can move with its notch 57 below the arm 56 of the stop lever 48 when the tensioning cam 172 provided at the slide shifting coupling 33, by means of a roller 173, has pushed back the stop lever 48 into the stop position represented in FIG. 5.

During the last step of the back movement directed to the left of the actuating rod 93 (FIG. 2) also a finger 174 rigidly connected with the link 95 strikes an upturned lug 175 of the locking lever 252 (FIG. 3) for the restoring rod coupling 29 which until now has been retained in its 180° turning position corresponding to the position of the restoring bar and rocks clockwise the locking lever 252 so that its lug releases the stop lever 250

5

(FIG. 6) for the restoring bar coupling 29 enabling it to perform the second half of its revolution on which the restoring bar 16 will be returned into its normal position.

At the end of this movement a tension cam 176 (FIG. 6) of this coupling rocks back the stop lever 46 clockwise through a roller 177, so that the stop lever again puts its left arm against the lug 51 of the locking lever 59 whereby the restoring bar coupling will be disengaged.

Therewith the rounding off cycle of operation has been performed under simultaneous striking off of decimal orders, addition of five units in the highest denomination struck off and the movement of the totalizer slide from its normal position to the right according to the number of denominations struck off, so that the main totalizer being kept ready in the correct denominational position for the transmission of its value to the printing mechanism, auxiliary totalizers or storing devices or back onto the multiplying mechanism.

20

Switching Off of the Revolution Counting Mechanism

During the rounding off cycle of operation the revolution counter must be inactive in order to avoid that it will be actuated by one unit during this cycle of operation according to the one revolution of the multiplying mechanism, since this revolution nothing has to do with the multiplier. The addition of one unity on each revolution of the multiplying mechanism 3 (FIG. 1) the revolution counter 12 is connected to the toothed wheel 178 (FIG. 6) engaging the driven part of the multiplying coupling 32. The toothed wheel 178 turns a wheel 181 provided with an eccentric pin 180 over an intermediate wheel 179. This wheel is secured to the already mentioned driving shaft 279 for the multiplier mechanism.

The eccentric pin 180 is connected by means of a link 182 with a push fork 183 which is guided by means of a pin 185, engaging a slot 186 of a change over lever 187 and by means of a link 184 loosely mounted on a stationary pivot. This push fork 183 cooperates by means of actuating lugs 188, 189 with a drive wheel 190 which is stationarily unslidably but rotatably mounted and non-rotatably connected with a slidable square axle 280 (FIGS. 6 and 3), on which an actuating wheel 281 is secured which can be brought into mesh with the different counting wheels 282 of the revolution counter by shifting the axle 280. This axle is connected with the totalizer slide 5 (FIG. 3) over a two armed lever 284 mounted on a fixed pin 283 and over pins 285 and 286 in such a way that on the shifting of the totalizer slide 5 on engagement of the slide shifting coupling 33 (FIG. 5) and on shifting of the totalizer slide 5 the actuating wheel 281 (FIG. 3) performs a corresponding shifting and the respective counting wheels 282 will be rotated by a number of actuating units corresponding to the number of revolutions of the multiplying mechanism.

In the middle position of the push fork illustrated in FIG. 6 the drive wheel 190 will be left uninfluenced by the oscillating movement of the push fork. When the push fork 183 is held, on its oscillating movement, in its left position an actuating lug 189 becomes effective, whereas the counting wheel 191 will be additively turned, whilst, on the adjustment of the push fork 183 in the right hand rocked position the actuating lug effects a subtractive further actuating of the counting wheel 191 being in mesh.

The change over from additive to subtractive actuation and vice versa will be effected by means of rocking of the change over lever 187 about its pivot 192 being brought about by a set plate 193 pivotally mounted on the pivot 192.

70

During the striking off cycle of operation, now, the push fork 183 will be moved into the represented inefficient middle position and being held therein by coming into contact of two setting edges 197 of a slide 198 with two pins 194 and 195 being located above or below of

75

the pivot 196 of the push fork 183, 184 and on the latter. The slide 198 being guided by means of a slot 199 on a stationary pivot 200 and by means of a lever 202 rotatably mounted on a stationary pivot 201. The lever 202 is connected to an arm 204, mounted on a stationary pivot 203 by means of the above mentioned link 139. The link 139 cooperates, as described, with the pivot 131 of the lever 132 (FIG. 2) to which the pawl 130 is attached.

As long as the pivot 131 (FIG. 6) is in its left normal position the setting edges 197 are out of mesh with the pins 194, 195 whereby the push fork 183 can be freely adjusted into its left or right locking position. When, however, the pivot 131 is adjusted into its right hand position 131', which occurs on arriving of the restoring bar at the position 16' during the striking off cycle of operation, the link 139 will be moved to the right resulting in a corresponding upwards shifting of the slide 198 and in an adjusting of the push fork 183 by means of the setting edges 197 and the pins 194 and 195 into the inefficient middle position. The lever 202 is provided with a finger 205 being in the normal position of the link 139 in contact with a stationary pivot 206.

What I claim, is:

1. In a calculating machine for computing and printing products of the class described with a shiftable main totalizer, stationary auxiliary totalizers and a printing mechanism, a multiplying mechanism, differential actuating racks cooperating with said totalizers, said printing mechanism and said multiplying mechanism having means for rounding off a number of orders at the right of the product including means for adding five units to the highest order to be rounded off, a setting means for adjusting the number of orders to be rounded off, means for automatically initiating a particular cycle of operation for rounding off following the computing of the product, means for laterally shifting said main totalizer with respect to said differential actuating racks from its normal position, in which its lowermost order registers with the differential actuating rack of the lowermost order, stepwise to the right and back into said normal position, means for automatically controlling, during said particular cycle of operation: first, said means for adding five units in the normal position of the main totalizer, secondly, said main totalizer shifting means for shifting the main totalizer to the right by a number of orders to be rounded off, thirdly said differential actuator racks for transmitting the rounded off value from said main totalizer by means of said actuating racks to said printing mechanism and said multiplying mechanism.

2. In a mechanism according to claim 1, an oscillating restoring bar for said actuating racks performing a forward and a backward stroke, drive means for said multiplying mechanism, a revolution counter ordinally indicating the number of revolutions of said multiplying mechanism, and operative connections between said restoring bar, on the one hand, and said means for initiating said rounding off cycle of operation, said driving means for said multiplying mechanism, said revolution counter and said shifting means for said main totalizer to the right, on the other hand, means for rendering effective said operative connections on arriving of said restoring bar at its forward stroke end position, whereby said rounding off cycle of operation, said driving means for said multiplying mechanism will be engaged, said revolution counter will be disengaged and said main totalizer shifting will be prepared.

3. In a mechanism according to claim 1, a lever plate, an oscillating restoring bar performing a forward and a backward stroke for rocking said leverplate into an operative position at the end of its forward stroke, a multiplying mechanism driving coupling, a stop lever therefor, a push rod cooperating therewith and being adapted to release it, a restoring bar driving coupling, a pin revolving therewith adapted to actuate said push rod for releasing said stop lever at the end of the first half of revo-

lution of the restoring bar coupling and a tensioning cam connected with said multiplying mechanism coupling adapted to bring back said stop lever into its stop position at the end of the one revolution of the multiplying mechanism.

4. In a mechanism according to claim 1, said means for rounding off comprising a set plate transversely shiftable with respect to said actuating racks, said plate having a locking edge for locking said actuating racks in their normal position, a recess provided in said locking edge for freeing the movement of one of the actuating racks by five actuation units, stepped lugs integral with said set plate, an actuating rod cooperating therewith, operative connections between it and said means for shifting said main totalizer to the right in dependence on the cooperation of said actuating rod with said set plate.

5. In a mechanism according to claim 1, an oscillating restoring bar for said actuating racks performing a forward and a backward stroke, a leverplate cooperating therewith, a set plate for rounding off having stepped lugs, a stepwise movable actuating rod for controlling the shifting of the main totalizer into its normal position after rounding off cooperating with said stepped lugs, a coupling for the drive of the restoring bar, a revolution counter, a drive coupling for the main shifting of the totalizer, and operative connections between said lever plate, on the one hand, and said set plate, said actuating rod, said restoring bar, said restoring bar coupling, said revolution counter, and said main totalizer shifting coupling on the other hand, whereby, at the end of the multiplying operation, the lever plate being displaced by said restoring bar locking itself in its displaced position, and causing said actuating racks to be locked by said set plate in their normal position, said restoring bar coupling to be engaged, said actuating rod to be moved onto said stepped lugs, the engagement of said totalizer shifting coupling and the disengagement of the actuation of the revolution counter to be prepared.

6. Mechanism according to claim 1, an oscillating restoring bar for said actuating racks performing a forward and a backward stroke, a lever plate rockable from a normal position to an operative position, a pawl rockably mounted on said lever plate having a lug cooperating with said restoring bar and being operatively connected with said means for rounding off, whereby on rounding off and in the stroke end position of the restoring bar said lug will be placed into the path of the restoring bar, by said rounding off means, carrying, when struck by the restoring bar, said leverplate along into its operative position.

50 7. In a mechanism according to claim 1, said means for automatically shifting said main totalizer comprising a spring urged actuating rod, a set plate having stepped lugs, a finger integral with said actuating rod for sensing said stepped lugs, two ratchet gears on said actuating rod, a retrograde pawl cooperating with one of said ratchet gears being operatively connected with said restoring bar, an actuating pawl cooperating with the other ratchet gear being operatively connected with said multiplying mechanism, means for disengaging said multiplying mechanism, whereby on rounding off after said actuating rod has been sensed said stepped lugs, said actuating rod will be stepwise returned to its normal position on each shifting step of said totalizer till the totalizer assumes its normal position.

65 8. In a mechanism according to claim 1, a multiplying mechanism coupling, a main totalizer shifting coupling, said means for automatically shifting said main totalizer comprising an actuating rod controlling the shifting of the main totalizer to the right after rounding off, means for disengaging said multiplying mechanism coupling at the end of the single revolution of the rounding off operation, means for engaging the main totalizer shifting coupling at the end of said single revolution, a locking means for maintaining said engaging of the main totalizer shifting coupling, and a locking device for securing the

coupling in its engaged state, operative connections between said locking means and said actuating rod whereby said locking device will be released on arriving of said actuating rod at its normal position.

9. In a mechanism according to claim 1, said means for automatically shifting said main totalizer to the right after rounding off comprising an actuating rod, an actuating pawl cooperating therewith, a main totalizer shifting coupling having a revolving pin, a lever mounting said actuating pawl, a multiplying mechanism coupling having a tensioning cam effecting the engagement of said totalizer shifting coupling, a locking device maintaining the engagement of this coupling, an oscillating restoring bar for said actuator racks performing a forward and a backward stroke, a three armed lever cooperating with said locking device, whereby the engagement of the main totalizer slide coupling being effected by said restoring bar on arriving at its stroke end position and the releasing of said locking device being effected by displacing said three armed lever.

10. In a mechanism according to claim 1, said means for automatically shifting said main totalizer comprising a spring urged actuating rod, a multiplying mechanism coupling, a tensioning cam thereof, a totalizer shifting coupling, a locking device for securing the engagement of the main totalizer shifting coupling, said locking device for securing the engagement of the main totalizer shifting

coupling, said locking device comprising a locking lug and a locking lever, a three armed lever carrying said locking lug, a link attached to said actuating rod cooperating with said locking lever, whereby said locking device being disengaged in the normal position of said actuating rod by the action of said link onto said locking lever.

11. In a mechanism according to claim 1, a revolution counter, means for actuating it by one unit on each revolution of said multiplying mechanism, comprising a push fork having a rocking pivot and acting for additive or subtractive actuation according to its rocking to the one or the other side of its inactive middle position, a slide having a set edge, two lugs on said push fork situated above and below of said rocking pivot, a restoring bar, operative connections between it and said slide, whereby on arriving of said restoring bar at the end of its forward stroke said slide will be moved onto said lugs of the push fork rocking it into its inactive middle position.
